HAROLD E. WARNER, OF WEST SPRINGFIELD, MASSACHUSETTS, ASSIGNOR TO THE
FISK RUBBER COMPANY, OF CHICOPEE FALLS, MASSACHUSETTS, A CORPORATION
OF MASSACHUSETTS

TUBE TESTING APPARATUS

Application filed April 13, 1929. Serial No. 354,729.

My invention relates to testing tanks for pneumatic tubes, more particularly to means for rotating the tubes when under water in the tanks.

3 In tanks of this character the drums or rolls that support the tubes hold the tubes tightly enough to seal any holes that may be in the tube at that portion adjacent the drum; as a result defects in the tubes at these 10 points will not be made apparent.

The object of my invention is to provide improved means for rotating the tubes to eliminate the chance of defective tubes passing through the tank without showing tell-tale bubbles.

In the accompanying drawings, which illustrate one embodiment of my invention,

Fig. 1 shows a plan view of a tube testing tank made in accordance with my invention;

Fig. 2 is a detail view showing the relative position of a chain carrying tube supporting rolls and roll revolving means;

Fig. 3 is a side elevation, on somewhat 25 smaller scale, of the tube testing tank;

Fig. 4 is a sectional view taken substantially on line 4-4 of Fig. 1; and

Figs. 5, 6, and 7 are detail views showing the rotation of a tube supporting roll.

30 The apparatus comprises a pair of chains 10 guided through a tank 11 mounted on a frame 12. The chains 10 are slowly drawn through the tank 11, being guided by ways made by angle irons 13, and driven by any suitable source of power, such as a motor and reduction unit A.

Fastened between the chains 10 are spaced cross channels 14, each carrying two bearings 15. Hinged on the bearings and straddling 40 the channels 14 are links 16 and 17 held together by studs 18. The upper part of the studs carry rolls 19 having wide tube-retaining flanges 20. The links 17 below the channels 14 carry rollers 21 adapted to ride in ways formed by angle irons 22. These ways are at their extreme separation at the central portion of the tank and converge at the ends of the tank. This converging will cause the rollers 21 associated with the same channel 45 to come toward each other and likewise

bring the rolls 19 on the same channel toward each other, thus making it easy to place over or remove a tube 23 from them, as shown.

At the portion of the tank 11 intermediate the converging portion of the ways 22 the tubes 23 are slightly stretched. This stretching tends to draw the tubes 23 about the supporting rolls 19 and thus seal any holes that may be in that portion of the tubes. To overcome this I fasten a plate 24 with a series 55 of lugs 25 projecting therefrom to the top flange 20 of the rolls.

Rotatable pins 26, adapted to engage with the lugs 25 as the chains and the mechanism 60 carried by the chains pass through the tank, 65 are carried by bearings 27 held on straps 28 fixed to the tank 11. With reference to the detail Figs. 5-7 the action of the pins 26 can be readily seen. Each pin 26, which is 70 stationary in relation to the rolls 19 which move with the chains 10, acts as a stop for one of the lugs 25, thereby giving its supporting roll a partial rotation as the roll moves by. This movement is conveyed to the tube about the roll, moving the tube as 75 indicated in the figures. The location of a valve stem 29 and the change in position of the tube segment will illustrate how the tube has moved, thus unsealing that portion of 80 the tube sealed by the roll 19 during the initial movement of the tube through the water.

As shown, a rotating device has been located on each side of the tank, and, while this is preferable, it is possible to secure satisfactory results by placing a rotating device 85 on one side only. For giving the tube 23 a greater movement I have placed two rotating pins on each side of the tank, but one of these may be omitted if the greater movement 90 is not desired.

Having thus described my invention, I 95 claim:

1. In a device of the character described a pair of spaced rolls adapted to carry a tube between them, plates on the said rolls presenting projecting portions, and pins in the line of travel of the said rolls adapted to engage with the projecting portions on the rolls and rotate the rolls as they are drawn past the pins.

2. A device for testing annular rubber tubes which comprises a tank adapted to hold a testing liquid, a conveyor provided with pairs of spaced rolls adapted to support the tubes to be tested and movable through the tank beneath the surface of the liquid, a plate secured to at least one of each pair of tube supporting rolls, a plurality of lugs projecting from the plate and a pin positioned in the path of said projections to engage the latter and thereby rotate the rolls and the tubes supported thereon.
3. In a device of the character described a pair of spaced rolls adapted to carry a tube between them during their travel through a water filled tank, a plate on the said rolls presenting projecting portions, and pins in the line of travel of the rolls adapted to engage with the projecting portions on the rolls to rotate the rolls as they travel past the pins.
4. In an apparatus of the character described a device for rotating tube supporting rolls comprising projections on each of said tube supporting rolls and a fixed pin adapted to engage the said projections and rotate the rolls as they are guided past the fixed pin.
5. In an apparatus of the character described, pivotally mounted tube supporting rolls, means for advancing said rolls, a series of lugs on each of said tube supporting rolls and a fixed pin in the line of travel of the rolls adapted to engage the said lugs and rotate the rolls as they are guided past the fixed pin.
6. In an apparatus of the character described, pivotally mounted tube supporting rolls, means for advancing said rolls, a series of lugs on each of said tube supporting rolls and a series of fixed pins in the line of travel of the rolls adapted to engage the said lugs and rotate the said rolls as they are guided past the fixed pins.
7. A device for testing annular rubber tubes which comprises a tank adapted to hold a testing liquid, a conveyor provided with pairs of spaced rolls adapted to support the tubes to be tested and movable through the tank beneath the surface of the liquid, projections on at least one of each pair of tube supporting rolls and a pin positioned in the path of said projections to engage the latter and thereby rotate the rolls and the tubes supported thereon.

HAROLD E. WARNER.
